UNITED STATES PATENT OFFICE.

JEROME B. SWEETLAND, OF PONTIAC, MICHIGAN.

ORE-PULVERIZER.

SPECIFICATION forming part of Letters Patent No. 292,384, dated January 22, 1884.

Application filed May 11, 1883. (No model.)

To all whom it may concern:

Be it known that I, JEROME B. SWEETLAND, of Pontiac, county of Oakland, State of Michigan, have invented a new and useful Improvement 5 in Ore-Pulverizers; and I declare the following to be a full, clear, and exact description of the invention, such as will enable others skilled in the art to which it pertains to make and use it, reference being had to the accompanying drawings, which form a part of this specification.

My invention consists in the construction and combination of devices hereinafter specified, and more particularly pointed out in the 15 claims.

In the drawings, Figure 1 is a plan view of one of the parts of an apparatus embodying my invention. Fig. 2 is a vertical section of one form of the device. Fig. 3 is a plan view 20 of a portion of the cover of the same. Fig. 4 is a plan view of the screen. Fig. 5 is a vertical section of one form of the device, showing a preferable construction in certain parts of the device. Fig. 6 is a plan view of the same 25 with the cover removed. Fig. 6' is a plan of the distributing-hopper, showing the three compartments thereto. Fig. 7 is a detail view of a portion of the same. Fig. 8 is a plan view 30 of the feeding apparatus. Fig. 9 is a vertical section of the same.

The object of my invention is to provide an improved ore-pulverizer, and is more especially designed as an improvement upon an ore-pulverizer for which Letters Patent were 35 granted to me dated January 30, 1883, No. 271,285.

In carrying out my invention, A represents the supporting-frame, of any suitable construction.

B is the shell or casing, the bottom of which is constructed with a discharge-orifice, as shown at b, Figs. 2 and 5. Said orifice may be of any suitable dimensions, and may be provided with a downwardly-projecting flange, 45 b', adapted to direct the pulverized ore in its discharge from the apparatus; or the flange may be omitted, as shown in Fig. 2. The shell may be provided with any suitable means whereby it may be secured to the frame—as, 50 for instance, by lugs b''. The shell is also pro-

vided with upwardly-projecting bolts b³, screw-nut upon their ends, by means of which the top of the shell or a portion thereof may be secured in place upon the shell. I desire to cast the sides, the bottom, and its fastening-lugs all in one piece, together with the bolts b³. I desire, moreover, to provide the shell with interior beveled projections or strips, b⁴, cast solid with the shell.

C is a ring concaved on its interior, adapted to fit into the interior of the shell B, and provided on its exterior with upright beveled projections or strips c, analogous to those upon the interior of the shell. The concave ring may have a shorter curve to the upper portion thereof, if desired, as shown in Figs. 5 and 7, the construction being such that an additional motion will be given to the balls when rotated, the balls having more contact on the upper portion of the ring than on the lower. 70 I do not, however, limit myself to such a construction, as the concavity of the ring may be constructed as shown in Fig. 2. The concave ring is also constructed with a suitable groove or channel upon either the top or bottom, or both, as indicated at c' and c'', into which suitable packing may be located, the packing serving to keep the pulverized dust or water from passing outside the concave ring, and also tending to hold the ring more firmly in place. 75 The base of the concave ring, as shown in Fig. 5, is located within the shell. I prefer, however, as shown Fig. 2, to broaden the discharge-orifice in the bottom of the shell and to extend the base of the concave ring through 80 the bottom of the shell to a suitable distance, the construction being such that a suitable discharge-hopper, C', may be secured thereto to hold the ring more firmly in place.

D is the web provided with a shaft, E, by 90 means of which it is revolved. This web may be constructed substantially as set forth in my patent above referred to, and is adapted to be revolved within the concave ring C, the balls d in the orifices d' of the web crushing the ore 95 against the concave ring. The web will be provided with movable adjusting-pins d', set into sockets formed in the web and bearing against elastic cushions therein, as described in my said former patent, to receive the back- 100

ward force of the balls and the wear and tear necessarily occasioned thereby, and to take up the wear of the balls, as described in said patent. Instead, however, of constructing the web precisely in this manner, I prefer, as shown in Figs. 1 and 2, to construct upon the upper side of the web a casing, D', either cast upon the web or secured thereto in any proper manner, said casing preferably projecting upward toward the center, thus providing a feeding-space, D², the feeding-space about the center of the web communicating with a suitable number of channels, d³, there being as many channels as there are balls to be rotated by the web. By this construction it is evident that when the ore is once fed into the space D² it will be prevented from being thrown by centrifugal force broadcast over the surface of the web, but will be thrown by centrifugal force through the channels d³, and thus fed directly in front of the balls as the web is rotated. The shaft of the web may be provided with a suitable pulley, F, of any suitable gearing, by which the web may be rotated. It is evident that when the web is rotated a strain will be communicated by the balls upon the concave ring. In order to communicate this strain to the shell, the shell and the ring are provided with the beveled projections b¹ and c, as hereinbefore described, the construction being such that the outer meeting faces of the projections are wedge-shaped in opposite directions, that the strain will continually tighten the concave ring in its location within the shell; and yet whenever it may be desired to remove the ring, by turning it in the opposite direction, it may also be readily disengaged and removed.

B' is the top of the shell. This may be constructed, as shown in Fig. 5, in one solid piece, provided with a hand-hole, B², said top being secured upon the shell by means of the bolts b⁵. Instead, however, of making the top in one piece, as shown in Fig. 5, I prefer the construction shown in Fig. 2, in which b⁷ is an annular plate secured upon the shell and extending over the upper edge of the concave ring, suitably provided with a groove upon its upper edge to receive suitable packing, as shown at b⁶. Upon this annular plate is secured the cover proper, B', said cover being provided with the hand-hole B².

To get more ready access to the interior of the apparatus for any purpose—such as the sampling of the ore and more thoroughly emptying the device when used by the assayer, and in order to more readily inspect the interior from time to time—I prefer that the cover should be so constructed that it may be lifted, as shown in Fig. 2, in which the cover is suitably hinged to the shell or plate, as shown at B⁴, by means of which the cover, together with the web, may be tilted, as shown in dotted lines in Fig. 2. The cover may be secured upon the plate in any suitable manner—as, for instance, by screws at b⁶. It will be seen that

by lifting the cover, as thus described, the whole interior of the shell is easily accessible either for inspection or for repairs.

G is a distributing-hopper located about the shaft E, and communicating with the interior of the shell by a suitable number of channels, said channels preferably corresponding in number to the number of the balls used, the interior of the hopper being also preferably constructed with a corresponding number of divisions, as shown in Fig. 6^a, directing the ore into said channels, the construction being such that the ore may be fed to each of the balls located at the periphery of the web, in order that each may have its proper share of the work.

G' is a sleeve encircling the shaft, so as to prevent any ore passing from the hopper against the shaft.

H is a feeding device supported in any suitable manner. The feeding device is constructed with a hopper, H', having a false bottom, H², covering a portion of the bottom of the hopper.

H³ is a vibrating apron, having three compartments, h, h', and h², communicating with the hopper H', and adapted to pass the ore over the top edge of hopper G into the three compartments thereof. The vibrating apron is pivoted to the false bottom H², the compartments h and h² being extended, so as to straddle the shaft E, said shaft being provided with a cam, f, adapted to vibrate the apron when the shaft is rotated.

h³ is a gate located in the hopper H', by means of which the feeding of the ore may be regulated as desired. By means of this feeding device it is evident that the ore may be more conveniently distributed to the balls within the shell.

The cover of the arm-hole B² may be secured by any suitable means, the construction being such that it may be readily removed, in order that the operator may look into the interior of the apparatus and adjust the balls or pins; or it may be removed, if necessary, without removing the entire cover from the shell. I prefer also to shrink upon the shell one or more hoops, B³, as shown in Fig. 5, to give additional strength and also permit the shell to be made of lighter casting than would otherwise be required, though this is not an essential element of my invention.

I prefer to provide the discharge-orifice with a screen. As shown in Fig. 2, this screen I is constructed to rest in the mouth of the discharge-hopper, the outer edges of the screen being provided with a beveled rim, a', which will fit against the inner face of the concave ring, as shown in Fig. 2, so as to prevent the ore from lodging thereon. It will be observed that the screen in this location is adapted to receive the balls when the cover with the web is raised, for when the web is lifted it is removed from contact with the balls, and they then fall onto the screen. This screen I is

shown more fully in Fig. 4. Should the discharge-orifice be contracted, as shown in Fig. 5, the screen may be secured upon an upwardly-projecting ring, K, as shown at k, said ring K being capable of firm adjustment in the discharge-orifice of the shell by means of screws or other suitable means. This construction is more particularly adapted for use in what is called the "wet process," when it may be desirable to have the water stand within the shell to a suitable depth, the ring K projecting upward for this purpose, thereby causing the properly-pulverized ore to pass through the screen at the top, while the unpulverized ore remains within the shell until ground sufficiently fine to pass through the screen. In case the dry process is used the screen might be omitted, if desired, in which case, also, the ring K shown in Fig. 5 would also be removed. I prefer the construction shown in Fig. 2, in which case the screen may be employed for both wet and dry processes. In case large balls are desired to be used at the periphery of the web, they may be constructed hollow should it be desired also to dispense with unnecessary weight.

It is evident that the ore-pulverizer, as thus constructed, may be cheaply manufactured and repaired, as all the parts which receive the wear—the concave ring, the balls and the pins against which they impinge, &c.—may be easily removed and replaced by duplicates of simple castings whenever desired.

I reserve the right to claim in another application all patentable features shown but not claimed.

What I claim is—

1. In an ore-pulverizer, a casing provided with upright beveled projections on its inner face, in combination with a detachable concave ring fitted within the casing, and provided with upright beveled strips on its outer surface, and adapted to engage with the beveled strips on the inner face of the casing, whereby the connection between the two parts may be tightened and loosened, substantially as described.

2. In an ore-pulverizer, the combination, with a casing, of detachable concave ring resting on the bottom of the casing, and provided with a downwardly-projecting base extending through an opening in the bottom of the casing, and a hopper attached to the lower edge of the ring below the bottom of the casing, substantially as described.

3. In an ore-pulverizer, the combination of the casing, the concave ring having a base extended through the casing, the hopper attached to the bottom of the concave ring, and the screen fitted against the inner face of the extended base of the ring and provided with an upwardly-extending beveled circumferential rim, substantially as described.

4. In an ore-pulverizer, the combination of a casing provided with beveled projections on its inner face, a concave ring provided with a groove in its top face to receive a packing, and with beveled strips on its outer surface to engage with the projections on the casing, as described, and a removable top fitting over the ring and casing and against the packing in the ring to hold the latter in place, substantially as described.

5. In an ore-pulverizer, the combination of a casing, a rotary web provided with loose balls at its periphery, and a casing, D', fitted over the web and adapted to direct the ore through suitable channels to the periphery of the web, substantially as described.

6. In an ore-pulverizer, the combination of a casing, an interior concave ring, an annular plate secured upon the upper surface of said casing and ring, and a hinged cover secured upon said plate, substantially as described.

7. In an ore-pulverizer, the combination of the casing, the annular plate fitting over the same, the cover hinged to the plate, and the packing between the plate and cover, substantially as described.

8. In an ore-pulverizer, the combination of the casing, a hinged cover thereto, a shaft passing through the cover, and the web secured to the lower end of the shaft, substantially as described.

9. In an ore-pulverizer, the combination of a casing, a distributing-hopper divided into compartments and provided with channels communicating with the casing, a feed-hopper, a vibrating apron divided into compartments communicating with said hopper and the compartments of the distributing-hopper, and a cam-shaft for vibrating the hopper, substantially as described.

10. In an ore-pulverizer, the combination of a casing having a concave face with a shorter curve at the upper portion than at the lower portion thereof, and a rotating web carrying loose balls at its periphery next to the concavity of the ring, substantially as described.

11. In an ore-pulverizer, an interior concave ring provided with upright beveled strips on its outer surface, and grooves for packing on its edges, substantially as described.

12. In an ore-pulverizer, the combination of a casing, a ring within the same, having a concave face with a shorter curve at the upper portion than at the lower portion thereof, a rotating web carrying loose balls at its periphery, and adjusting-pins set in the web opposite to the balls, substantially as described.

In testimony whereof I sign this specification in the presence of two witnesses.

JEROME B. SWEETLAND.
